UNITED STATES PATENT OFFICE.

ALBERT SCHMID, OF ALLEGHENY, ASSIGNOR, BY MESNE ASSIGNMENTS, TO THE WESTINGHOUSE ELECTRIC AND MANUFACTURING COMPANY, OF PITTSBURG, PENNSYLVANIA.

FIELD-MAGNET FOR ELECTRIC MACHINES.

SPECIFICATION forming part of Letters Patent No. 519,097, dated May 1, 1894.

Application filed December 7, 1889. Serial No. 332,961. (No model.)

To all whom it may concern:

Be it known that I, ALBERT SCHMID, a citizen of the Republic of Switzerland, residing in Allegheny, in the county of Allegheny and 5 State of Pennsylvania, have invented a new and useful Improvement in Field-Magnets for Electrical Machines, (Case No. 363,) of which the following is a specification.

The invention relates to the construction of 10 the field-magnets of generators and motors.

The object of the invention is to simplify the construction and lessen the cost of the field-magnets of electric machines and at the same time secure certain improved results.

15 The invention consists in constructing the pole-pieces of the field-magnets of laminæ of sheet iron stamped or cut into the proper form, and supporting the same in a frame of cast metal. The laminæ after having been

20 stamped are assembled in the proper relative position and held in any suitable manner, and the molten metal to form the frame is cast about them in suitable molds. The laminæ of soft iron may be insulated from each other

25 to a greater or less extent by oxide of iron formed upon their adjacent surfaces, thus preventing the circulation of Foucault currents.

The invention will be described more in detail in connection with the accompanying 30 drawings, in which—

Figure 1 is an end view of the field-magnet and Fig. 2 a cross-section of the same. Figs. 3, 4 and 5 illustrate details.

Referring to the figures A represents the 35 frame of the field-magnet and B, B, field-magnet poles. These poles are composed of laminæ or plates *b* of soft iron, such as sheet iron. These laminæ are stamped out in the proper shape and size and are assembled in their 40 proper relative positions in the molds. They may be bolted or otherwise secured together as illustrated at *c*. For the purpose of secur-

ing a good union between the sheet iron and the cast iron, some of the laminæ may be made of greater length than the others as 45 illustrated in Figs. 4 and 5 so that the ends will afford openings into which the molten metal will run; some of the laminæ may be made with laterally projecting lugs as shown at *f*, around which the cast iron will flow, 50 thus making the mechanical structure more firm. The field-magnet frame may with advantage be cast in separate portions as shown at *a'*, *a''*. This permits the armature to be more easily placed in the field-magnet and secures a better mechanical construction than 55 would be obtained by forming it in one continuous piece. This form of field-magnet possesses the advantages of laminated field-magnet cores, such as are especially desirable for 60 alternating current apparatus and at the same time secures the cheapness and simplicity of construction of the ordinary cast-iron field-magnets.

I claim as my invention—

1. In an electric generator or motor for alternating currents, field-poles composed of laminæ of sheet iron, a frame for said poles of cast-iron cast about the laminated pole pieces, certain of the laminæ projecting into the cast 65 iron frame a greater distance than the others.

2. In an electric generator or motor for alternating currents, field-poles composed of laminæ of sheet iron placed in contact with each other, a frame for said poles of cast iron, 70 certain of the laminæ having lateral lugs, substantially as described.

In testimony whereof I have hereunto subscribed my name this 5th day of December, A. D. 1889.

ALBERT SCHMID.
